UNITED STATES PATENT OFFICE.

JAMES A. ILLINGWORTH, OF SPRINGFIELD, MASSACHUSETTS.

UPHOLSTERY-BRUSH.

SPECIFICATION forming part of Letters Patent No. 275,827, dated April 17, 1883.

Application filed October 30, 1882. (No model.)

To all whom it may concern:

Be it known that I, JAMES A. ILLINGWORTH, of Springfield, in the county of Hampden and State of Massachusetts, have invented a new and useful Improved Upholstery-Brush, of which the following is a specification and description.

The object of my invention is to provide a brush adapted to reach and remove the dust and dirt which accumulate in the recesses and around the buttons in tied upholstery; and I accomplish this by the mechanism substantially as hereinafter described, and illustrated in the accompanying drawings, in which—

Figure I is a perspective view of an upholstery-brush made according to my invention. Fig. II is a longitudinal section of the same at its apex; and Fig. III is a sectional view of the brush, showing its application to use in cleaning upholstery.

In the drawings, 1 represents the handle and body of the brush, which may be made of any desired material—such as wood, papier-maché, hard rubber, or any other suitable substance—into which are inserted the bristles 2, which are to form the brush proper, these bristles being inserted at and all around the end of the body 1, and secured in any well-known manner, so that they may extend out from the end of the body in the direction substantially as shown in Fig. II, so that they may operate effectually when the end of the brush is placed against any fabric to be cleaned. At the end of the brush, in line with the body 1, a concave recess, 3, is made therein, either by cutting the bristles out at their ends to give that concave form, or by securing the bristles in the end of the body 2 of such relative length each to the others as to give that concave recessed form. This con-

cave recess 3 is of such form as to approximately fit the exposed surface of the ordinary buttons with which upholstery is usually tied or fastened, with substantially the same pressure of each bristle against the button when the end of the brush is placed in the recess of the upholstery to clean it out, while the bristles immediately surrounding this concave recess press with substantially the same pressure against the fabric in the recess of the upholstery to clean it.

In cleaning the dust and dirt from the buttoned recesses in upholstered furniture the end of the brush is placed in a recess, with the button therein in the concave recess 3 in the end of the brush, and the latter is rotated to and fro by the handle 1, which may have a cross-piece, 4, attached for convenience, if desired, and a few rotary movements of the brush will thoroughly clean the dirt and dust from the button and from the fabric within the recess surrounding it in a manner that could not be accomplished by any other means.

The straight portion of the brush may be used for cleaning the plainer surfaces of the upholstered fabric in the usual manner.

Having thus described my invention, what I claim as new is—

An improved brush for cleaning upholstery, consisting of the body 1, having the bristles secured thereto all around the end, with a concave recess formed in the outer end of the mass of bristles at the end of the brush, adapted to approximately fit the buttons, and to clean the latter and the adjacent fabric, substantially as described.

JAMES A. ILLINGWORTH.
